UNITED STATES PATENT OFFICE.

CHARLES PETERSEN, OF CORVALLIS, OREGON.

METAL COLLAPSIBLE CHICKEN-COOP.

1,047,561.

Specification of Letters Patent. Patented Dec. 17, 1912.

Application filed October 10, 1910. Serial No. 586,420.

To all whom it may concern:

Be it known that I, CHARLES PETERSEN, a citizen of the United States, residing at Corvallis, in the county of Benton and State 5 of Oregon, have invented new and useful Improvements in Metal Collapsible Chicken-Coops, of which the following is a specification.

My invention relates to knock down metallic chicken coops, and it consists in the construction and arrangement of parts, as will be hereinafter described and particularly pointed out in the claim.

The figure of the drawing represents a 15 perspective view of my improved coop.

I wish it to be understood that my structure of coop is made of solid sheets of metal as shown in the drawing, and the numeral 1 designates the front wall thereof having 20 oppositely disposed oblique upper ends provided with a continuous surrounding outwardly disposed flange 3.

The numerals 4 and 5 designate the side walls, the opposite ends of which are bolted 25 to the flanged portion of the front wall below the oblique portion of said flange. The side walls are each provided with outwardly extended flanges 7 and 8 on their upper and lower ends, the lower ones of which are bolted 30 to the floor 6.

The numerals 9 and 10 designate the roof sections, the latter having a longitudinal flange 11 which contacts with and is bolted to the upper flange of the side wall 4 and 35 also bolted to one of the oblique portions of the front wall. The other section 9 of the roof is provided with a downwardly extended flange 12 which overlaps the upper portion of the roof section 10 and is bolted 40 thereto and to the flanged oblique portion under the section of the roof 10. Said section of roof 9 also having an outwardly extending flange 14, which is bolted to the flange on the upper portion of the side wall

5. The front wall is provided with reticulated ventilating openings 15 in its oblique portion. A detachable anchor rod 16 with an operating handle 16' thereon is inserted through the apex of the two roof sections and contacts with the front wall of the coop 50 and has its lower end projecting through the floor and through that portion of the flange 3 of the front to which the floor is bolted and also penetrates the ground. A door is hinged to the rod 16 to permit of 55 access being had to the coop.

I wish it to be understood that the rear wall of the coop is constructed the same as the front wall thereof, with the exception of the door way and has a rod 17 arranged the 60 same as the rod 16.

The structure as above described is easily taken apart and packed together so as to permit of the same being readily removed from one place to another. 65

Having described my invention what I claim is:—

A knock down coop, comprising front and rear walls, side walls secured to the front and rear walls, roof sections connected at 70 their outer edges to the side walls, one of said roof sections being formed with a flange overlapping the adjoining edge of the other roof section and bolted thereto, a floor connected to the lower edges of the 75 front, rear and side walls, anchoring rods extending downwardly through the flange of said roof section and through the underlying portion of the other roof section and downwardly and entirely across the front 80 and rear walls, and a swinging door mounted for its opening and closing movements on one of said anchoring rods.

CHARLES PETERSEN.
